UNITED STATES PATENT OFFICE

ANTON BIEN, OF MOUNT VERNON, ILLINOIS

PORCELAIN-ENAMEL WARE-FUSING TRAY

Application filed May 17, 1929. Serial No. 363,968.

This invention relates to an article assembling and carrying tray expressly designed for use in enamel furnaces while fusing porcelain enamel onto various articles of ⁵ cast iron and steel.

The present and old method of assembling and placing the enamel coated articles in the fusing furnace is characterized by many difficulties and inconveniences which render it ¹⁰ most unsatisfactory. The devices now used for this work comprise built up holders which are stacked in tiers in a vertically superposed manner. Each device consists of a multiplicity of bars, loops and risers. These are ¹⁵ separate elements and must be assembled and disassembled piece by piece for every load. For instance, first, the castings on the top tier in this assembling must be removed in order to permit access to be had to those on the ²⁰ tier or rack beneath, then the castings on the middle tier are removed and this tier is disassembled piece by piece, etc. The assembling and reloading operation consumes much time and requires considerable skill and ²⁵ care in order to avoid the production of poor work. The fact is that unusual care must be exercised in these operations to prevent undue spoilage, particularly where multi-color coating enamels are employed.

Without delving further into the difficulties experienced in the present method of handling and stacking it is only necessary to say that the present one-piece tray has been especially designed with a view to ³⁰ ward overcoming the objections and difficulties.

In carrying the present invention into effect and practice I have evolved and produced a simplified and economical structure which ⁴⁰ is highly practicable in arrangement and such as to facilitate and expedite handling, assembling, disassembling and other work, thus the improved tray better fulfills the requirement of this particular work.

⁴⁵ Other features and advantages will become more readily apparent from the following description and drawings.

In the drawings:

⁵⁰ Figure 1 is a side elevational view showing a plurality of the improved trays, con-

structed in accordance with the invention, racked into the customary tier formation, the lower tray resting on the customary supporting rails.

Figure 2 is a side view of one of the trays ⁵⁵ by itself.

Figure 3 is an enlarged end view of the tray.

Figure 4 is a top plan view thereof.

Figure 5 is a cross sectional view taken approximately on the line 5—5 of Figure 4. ⁶⁰

Figure 6 is an enlarged fragmentary detail corner section taken approximately upon the plane of the line 6—6 of Figure 4.

Each tray as seen from Figures 2, 3, and 4 ⁶⁵ is in the form of an open work grid or frame structure. The parts are formed of chrome and nickel or any other such metal or composition sufficient to withstand the excessive heat and to prevent warpage while in the enamel fusing furnace. Each tray is generally designated by the reference character 7 as seen in Figure 4 comprises longitudinal side bars 8 connected together by transverse end bars 9. In addition, there are longitudinal intermediate spaced parallel bars 10 and transverse bracing bars 11. The latter bars being arranged in staggered relationship. All of the bars are substantially diamond ⁷⁰ shaped in cross section to provide the smallest degree of contact with the enamel article (not shown). In other words the contact surface between the tray and the article supported thereon is so made as to minimize the surface contact and to prevent marring of ⁷⁵ the coated surfaces of the article. Attached to and rising from the opposite end bars 9 are short risers or posts 12 whose upper ends are formed with V-shaped notches 13 to receive the complementary end bars of the superposed tray as seen in Figure 1. This permits the tray to be stacked in the desired tier formation and prevents accidental displacement and facilitates handling.

From the foregoing description it will be ⁹⁵ seen that the gist of the invention is in the production of a one piece article carrying tray of appropriate proportion and strength, the tray being composed of metal such as will prevent distortion while in the furnace, ¹⁰⁰

each tray being characterized by an open work grid structure wherein the bar members are diamond shaped in cross section and the end bars equipped with appropriate supporting risers.

It will be apparent to persons skilled in the art to which this invention relates that these one piece trays made of chrome and nickle composition replace the wood trays that are loaded by grainers and sprayers and are placed on furnace chargers in full racks four tiers high in the space where three tiers are placed in the old method. There are no bars or castings to be moved, no danger of rubbing of enamel or dirt to fall on lower tiers for each rack sets with its lower surface edges firmly seated in the risers of the adjacent tray beneath. Twenty-four to twenty-eight of these trays may be placed in the enamel furnace at one time on stove castings, such as for instance stove legs, fronts, tops, doors, backs, or any other parts. It is entirely unnecessary for the burners and helpers to touch the castings. This effects an unusual saving in otherwise destracted asbestos gloves that are burned up when handling hot castings piece by piece as in the old method. These trays come direct from the drying process or graining process to the enamel furnace on platforms, are loaded on chargers and placed in the enamel furnace. In other words the work is allowed to remain on the trays during the various steps in the application of the coating material and the fusing as well as the spraying and other extra handling. If they come from the grainer, then they are placed on platforms to be taken into the inspector or packer or store room. There is no dumping about such as causes chipping and damaging of the enamel coating. All told, these one piece metallic trays will greatly expedite the handling of various types of articles, and will overcome the difficulties and objections experienced in the old and seemingly crude method now followed. It is thought however that persons familiar with the old method and the improved tray will clearly appreciate the advantages accompanying the same. Therefore, a more lengthy description is regarded unnecessary.

Minor changes in shape, size, and rearrangement of details coming within the field of invention may be resorted to in actual practice if desired.

Having thus described the invention, what I claim as new and desire to secure by Letters Patent is:—

1. As a new product of manufacture, a one piece enameling tray composed of metal and including a horizontal rack having a plurality of interconnected bars disposed in spaced relation, and integral vertically disposed supporting posts carried by the end bars of said rack.

2. As a new product of manufacture, a one piece enameling tray composed of metal and including a horizontal rack having a plurality of interconnected bars disposed in spaced relation, and integral vertically disposed supporting posts carried by the end bars of said rack, said bars and said posts being of diamond shaped cross section for the purposes specified.

In testimony whereof I affix my signature. 75
ANTON BIEN.
